UNITED STATES PATENT OFFICE.

MORRIS ABBOTT VAN NOSTRAND, OF NEW YORK, N. Y.

DESIGN FOR A TEAPOT OR SIMILAR ARTICLE.

Application filed July 30, 1924. Serial No. 10,325. Term of patent 7 years.

To all whom it may concern:

Be it known that I, MORRIS A. VAN NOSTRAND, a citizen of the United States, and a resident of the city of New York, borough of Manhattan, in the county and State of New York, have invented a new, original, and ornamental Design for Teapots or Similar Articles, of which the following is a specification, reference being had to the accompanying drawings, forming part thereof.

Figure 1 is a view in side elevation of a teapot showing my new design;

I claim:

The ornamental design for a teapot or similar article, as shown.

MORRIS ABBOTT VAN NOSTRAND.
